[57] CLAIM

The ornamental design for a mounting for a window or a door, as shown.

DESCRIPTION

FIG. 1 is a perspective view, showing a first embodiment, of

my new design of a mounting for a window, or a door with the base plate in a partially rotated position;

FIG. 2 is a bottom plan view of the mounting shown in FIG. 3;

FIG. 3 is a front elevational view of the mounting shown in FIG. 1 with the base plate shown aligned with the latch member;

FIG. 4 is a left side elevational view of the mounting shown in FIG. 3;

FIG. 5 is a right side elevational view of the of the mounting shown in FIG. 3;

FIG. 6 is a rear elevational view of the mounting shown in FIG. 3;

FIG. 7 is a top plan view of the mounting shown in FIG. 3;

FIG. 8 is a reduced front elevational view showing a second embodiment of the base plate, shown separately for ease of illustration;

FIG. 9 is a reduced front elevational view showing a third embodiment of the base plate, shown separately for ease of illustration;

FIG. 10 is a reduced front elevational view showing a fourth embodiment of the base plate, shown separately for ease of illustration;

FIG. 11 is a reduced front elevational view showing a fifth embodiment of the base plate, shown separately for ease of illustration;

FIG. 12 is a reduced front elevational view showing a sixth embodiment of the base plate, shown separately for ease of illustration; and,

FIG. 13 is a reduced front elevational view showing seventh embodiment of the base plate, shown separately for ease of illustration.
